COMBINED CIGARETTE AND MATCH CASE AND ASH TRAY

Filed Dec. 12, 1928

*Inventor:
L. Archibald Garner,
by John O. Brady, his Attorney.*

Patented June 11, 1929.

Des. 78,706

UNITED STATES PATENT OFFICE.

LORRAINE ARCHIBALD GARNER, OF LOS ANGELES, CALIFORNIA.

DESIGN FOR A COMBINED CIGARETTE AND MATCH CASE AND ASH TRAY.

Application filed December 12, 1928. Serial No. 29,233. Term of patent 14 years.

To all whom it may concern:

Be it known that I, LORRAINE ARCHIBALD GARNER, a citizen of the United States of America, residing at Los Angeles, in the county of Los Angeles and State of California, have invented a new, original, and ornamental Design for a Combined Cigarette and Match Case and Ash Tray, of which the following is a specification, reference being had to the accompanying drawing, forming part thereof.

Figure 1 is a side view of the combined cigarette and match case and ash tray of my invention; and Fig. 2 is a rear view of the combined cigarette and match case and ash tray.

I claim:

The ornamental design for a combined cigarette and match case and ash tray as shown.

LORRAINE ARCHIBALD GARNER.
